Primary Examiner — Joseph Kukella*Assistant Examiner* — Heather Wencl(74) Attorney, Agent, or Firm — Dunlap Bennett & Ludwig PLLC; Anna L. Kinney(57) CLAIM

The ornamental design for a tower trophy, as shown and described.

DESCRIPTION

FIG. 1 is a top front perspective view of a tower trophy, showing my new design;

FIG. 2 is a bottom rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines shown in the drawings depict portions of the article that form no part of the claimed design.

1 Claim, 8 Drawing Sheets(56)
